UNITED STATES PATENT OFFICE.

JOSEPH B. MURRAY AND THOMAS E. MURRAY, JR., OF BROOKLYN, NEW YORK.

HEAT-CONDUCTING TUBE AND METHOD OF MAKING THE SAME.

Application filed June 18, 1924. Serial No. 720,737.

In certain prior applications, Nos. 642-427 filed May 31, 1923, and 642,725 filed June 1, 1923, there is described a certain hollow construction for walls and other parts 5 of boilers or heaters and made up of tubes of rectangular, circular or irregular cross-section with fins or flanges extending lengthwise thereof so as to provide a heating surface exposed to the heating gases greater 10 than the surface which is in contact with the water or other fluid in the tube.

The present invention provides a unit and a method of producing the same from which such boiler walls and the like may be built. 15 The accompanying drawings illustrate embodiments of the invention.

Fig. 1 is a horizontal section of a side wall of a boiler built with the tubular units of the invention;

20 Figs. 2 to 5 are plans of various forms of units made in accordance with the invention.

In an application co-pending herewith, Serial No. 715,369, filed May 23, 1924, there 25 are described special forms of units and methods of production thereof. The present application covers specifically distinct constructions for such units.

According to Fig. 1, an inner wall or 30 screen for a boiler is made of tubes 1 each of which has at one side a lateral flange 2 extending to the next tube and approximately closing the space between the two tubes, while leaving freedom for relative 35 movement under the distortion produced by heat. Back of the screen thus described is an ordinary boiler wall made of refractory bricks 3, insulating tiles 4 and a shell 5 of sheet steel.

40 The present application is directed to the production of units for the building of such a wall in which the flanges on the tubes are integral with the walls of the tubes 1. This result is obtained in Fig. 2 by bending a 45 sheet, leaving a portion 2 flat to form the flange and bending the remainder around to form a tube 1 with its free edge abutting the part 2 at its inner edge, and arc welding the edges together by means of deposited metal 6, or butt welding them, or uniting them by both means.

50 Fig. 3 is similar to Fig. 2 except that the free edge of the tube 1 is flanged and lapped

over the inner edge of the part 2, as at 55 7; the parts being welded together as before.

There are advantages in providing two flanges on each tube, one at either side, since a given space between adjacent tubes can be covered with flanges of less width, which 60 provide shorter paths for transmission of the heat to the tubes. For obtaining two integral flanges the arrangement of Fig. 4 is suitable. Here the unit is made of two identical pieces each with a flat flange portion 8 and a substantially semi-circular portion 9; the edges of the parts 9 being butted against the inner edges of the parts 8 as shown and welded as in the previous cases.

Generally speaking it appears preferable 70 that each tube with its flange or flanges shall constitute a separate unit. But there are cases in which it may be desirable to make up one complete unit of two or more tubes.

Fig. 5 illustrates a construction of this 75 sort. The unit is made of two pieces of sheet metal each comprising an outer flange 10 with an adjacent semi-circular portion 11, an intermediate web or flange 12 and a second semi-circular portion 13, these parts being 80 brought together so as to form two parallel tubes with an intermediate web and with flanges 10 at the sides and being welded together as at 6 and preferably spot welded as at 14 to prevent separation of the parts 85 12 under the pressure within the tubes. Units of this sort will be placed alongside of one another, as indicated at the left of the figure, with the respective flanges 10 overlapping.

Though we have described with great particularity of detail certain embodiments of our invention, yet it is not be understood therefrom that the invention is restricted to the particular embodiments disclosed. Various modifications may be made by those skilled in the art without departure from the invention as defined in the following claims.

What we claim is:

1. A tubular heat conducting unit for boilers and similar apparatus comprising a tubular portion of closed cross-section throughout its length and a longitudinal flange portion, the unit being made up of sheet metal 105 of uniform thickness, a portion of the width

of which constitutes the flange portion of the unit and another portion of the width of which sheet is bent to form the tube.

2. The method of making a tubular heat conducting unit for boilers and similar apparatus which consists in forming a tube by bending around a portion of the width of a sheet which is continuous throughout its length so as to form a tube of closed cross-

section throughout its length, and welding the bent around edge in a continuous lengthwise joint leaving the remaining portion of the width of the sheet as an integral flange extending lengthwise of the tube.

In witness whereof, we have hereunto signed our names.

JOSEPH B. MURRAY.

THOMAS E. MURRAY, JR.
